ABSTRACT: An elongated resilient clip rectangular in cross section has a flat end bearing portion and an arcuate end portion to engage the lower face of a railway tie and the lower side of a cover plate on a bridge girder. Said arcuate portion has an elongated slot, upwardly through which and through the tie, passes a bolt which has a head at one end underlying said arcuate portion and means at its other end to tense the bolt.

RAILROAD BRIDGE TIE ANCHOR

BACKGROUND OF THE INVENTION

1. Field of the Invention

This invention relates particularly to means for securing or anchoring railway ties on a bridge. Railway bridges are composed essentially of wooden crossties laid at right angles to the actual load carrying rails and supported by steel girders that are at right angles to the ties that they support and hence, parallel, with the load carrying rails.

The ties on one bridge may differ in dimensions from the ties on other bridges. Generally, the girders have cover plates beneath the ties, and the cover plates in one bridge may differ in thickness from the cover plates in another bridge.

The load carrying rails are fixed to the ties and are subject to expansion and contraction during extremes of temperature, and this causes the underlying ties to shift forward and backward along the bridge girders resulting in wear and general deterioration of the bearing surfaces of the ties, with the resultant danger of derailment of trains with loss of life and valuable equipment as well as freight. Also the wooden ties shrink as a result of alternate wetting and drying.

2. Description of the Prior Art

There is a need for satisfactorily securing the ties on a bridge. Bridge tie anchors heretofore in use comprise a resilient curved plate having one end abutting the bottom surface of the tie and its other end slidably abutting the underside of a cover plate or girder flange and having a circular bolt hole of about the same diameter as a bolt which passes through the hole and through the tie and has a head at one end and a nut on the other end, one of which underlies the plate while the other is above the tie to tense the bolt.

However, these known anchors do not permit the use of the anchors with cover plates of substantially different thicknesses, so it is necessary to carry an inventory of anchors of different sizes and shapes.

SUMMARY

A primary object of the present invention is to provide a bridge tie anchor embodying novel and improved features of construction which will continuously ensure a firm clamping of the tie on a bridge girder despite shrinkage of the wooden tie, which will ensure adequate resilient clamping of ties on bridges having cover plates of different thicknesses so that the same anchor may be used on different bridges and thereby eliminate the necessity for a large inventory of anchors of different sizes.

In general the invention provides an elongated resilient clip rectangular in cross section and having a flat end bearing portion to engage the lower face of a tie and also having its opposite end portion arcuate and spaced longitudinally of the clip from said bearing portion. Said arcuate portion having an elongated slot extending longitudinally of the clip to receive a bolt which is of a diameter substantially less than the length of the slot and such as to slidably engage the sides of the slot, providing for swinging of the clip about the free extremity of said bearing portion and relatively to the bolt for adjusting the position of the extremity of the arcuate portion so that the clip can be used with cover plates or girder flanges of substantially different thicknesses.

A BRIEF DESCRIPTION OF THE DRAWING

FIG. 1 is a side elevational view of one end of a tie and the bridge tie anchor embodying the invention, mounted on cover plates of a bridge girder that is shown in fragmentary cross section;

FIG. 2 is a greatly enlarged fragmentary side elevational view of the bridge tie anchor and a tie and cover plate;

FIG. 3 is a top plan view of the resilient clip; and

FIG. 4 is an end elevational view of the clip.

DESCRIPTION OF THE PREFERRED EMBODIMENT

Referring to the drawing, reference character A designates a wooden tie one end of which is seated on cover plates B for a bridge girder C. The other end portion of the tie is similarly set on another bridge girder and the usual rails D are secured to the tie by spikes E. Passing through the tie adjacent each end thereof is a prebored hole through which passes a bolt F having a head 1 underlying a resilient clip G and having at its other end means such as a nut 2 above the tie for tensing the bolts.

The resilient clip comprises an elongated piece of resilient material, particularly heat treated steel, which is rectangular in cross section and has a flat end bearing portion 3 having projections, for example upturned corners 4 to be imbedded in the lower face of the tie. The other end portion 5 of the clip is arcuately curved about a center or axis 6 and with a radius 7 which is determined by the general dimensions of the bridge structure to which the anchor is to be applied. Spacing apart the end bearing portion 3 and the arcuate portion 5 is an approximately straight portion 8. The arcuate portion has an elongated slot 9 extending longitudinally of the clip and having its ends approximately equidistantly spaced from the ends of the arcuate portion, the length of the slot being substantially greater than the diameter of the bolt and the width of the slot being such that the sides of the slot slidably engage the bolt F.

The intermediate portion 8 is angularly related to the plane 30 of the flat end bearing portion 3, and the imaginary center 6 of the arcuately curved portion 5 is located at the side of the plane of said flat end portion opposite said intermediate portion.

In use, the bolt is inserted through the slot 9 and the tie and the clip is located with its end bearing portion 3 abutting the lower face 10 of the tie and with the extremity of the arcuate portion slidably abutting the bottom face 11 of the cover plate. The nut 2 or other means for tensing the bolt is applied to the upper end of the bolt above the tie, a washer 12 preferably being used between the nut and the tie. The nut is tightened until the arcuate portion is flexed to apply the desired resilient pressure to the tie and the cover plate or girder for securely clamping the tie against movement.

For accommodating cover plates of different thicknesses, the clip is swingable about the end bearing portion 3 and relatively to the bolt so that for the thicker cover plates the clip will be positioned as shown by solid lines in FIG. 2 and for thinner cover plates the clip will assume the position shown by 50 dot and dash lines in FIG. 2. In all positions of the clip, the axis or center of the arcuate portion lies in an axial plane of the bolt and the axis of the bolt is coincident with a radial line of the arcuate portion as best shown in FIG. 2 where the center of the arcuate portion in the two positions of the clip are indicated by the reference numerals 6 and 6', respectively. With this construction, in all positions of the clip, the arcuate portion engages the bolt head in a radial plane of the arcuate portion and an axial plane of the bolt so that a firm balanced engagement between the bolt head and the clip is ensured at all 60 positions of the clip. The slot permits such swinging of the clip and the straight portion 8 of the clip provides the length which in turn permits the required pivotal action of the clip to accommodate cover plates or girder flanges of different thicknesses, while ensuring the relationship of the arcuate portion to the bolt above described. The clip in all of its positions affords adequate spring action to firmly hold the tie on the girder and to compensate for shrinkage of the ties and the bridge structure.

I claim:

1. The combination of a wooden tie resting on a girder having a cover plate, an elongated resilient clip rectangular in cross section and having a flat and bearing portion engaging the lower face of said tie, the corners of said bearing portion 75 being bent up and embedded in said tie; an arcuately curved

opposite end portion of said resilient clip slidably engaging the lower face of said cover plate and free to move thereon as said resilient clip is flexed, said arcuately curved portion having a slot extending longitudinally of said clip with its ends approximately equidistant from the ends of said arcuately curved portion, a bolt passing upwardly through said slot and said tie with its head abutting the underside of said arcuately curved portion and with its axis coincident with a radial line of said arcuately curved portion, a nut threaded on the upper end of the bolt and engaging above the tie whereby to tense said bolt and flex said clip, said clip being swingable about the free extremity of said bearing portion and relatively to said bolt for adjusting the position of said extremity of the arcuately curved portion to accommodate cover plates of different thickness.

2. The combination as defined in claim 1 wherein said clip has an approximately straight portion spacing apart said flat end bearing portion and said arcuately curved portion.

3. The combination of a wooden tie resting on a girder having a cover plate, an elongated resilient clip rectangular in cross section and having a flat end bearing portion engaging the lower face of said tie, said bearing portion having projections embedded in said tie, said clip also having its opposite end portion arcuate and spaced from said bearing portion, the free extremity of said arcuate portion slidably engaging the bottom face of the cover plate and being free to move thereon as said clip is flexed, there being an elongated slot extending longitudinally of the clip intermediate the ends of said arcuate portion, a bolt extending upwardly through said slot and said tie with its head underlying said arcuate portion, the bolt being of a diameter substantially less than the length of the slot and such as to slidably engage the sides of said slot, means at the other end of the bolt above the tie to tense the bolt and flex the clip, said clip being swingable about the free extremity of said bearing portion and relatively to said bolt for adjusting the position of said extremity of the arcuate portion to accommodate cover plates of different thickness.

4. The combination of a wooden tie resting on a girder having a cover plate, an elongated resilient clip rectangular in cross section and having a flat end bearing portion engaging the lower face of said tie, said bearing portion having projections embedded in said tie, said clip also having its opposite end portion arcuate, the free extremity of said arcuate portion slidably engaging the bottom face of the cover plate and being free to move thereon as said clip is flexed, there being an elongated slot extending longitudinally of the clip intermediate the ends of said arcuate portion, a bolt extending upwardly through said slot and said tie with its head underlying said arcuate portion, the bolt being of a diameter substantially less than the length of the slot and such as to slidably engage the sides of said slot, means at the other end of the bolt above the tie to tense the bolt and flex the clip, said clip being swingable about the free extremity of said bearing portion and relatively to said bolt for adjusting the position of said extremity of the arcuate portion to accommodate cover plates of different thickness.

gated slot extending longitudinally of the clip intermediate the ends of said arcuate portion, a bolt extending through said slot and said tie with a head at one end and means at its other end to tense the bolt one of which underlies the arcuate portion of the clip while the other is above the tie, the bolt being of a diameter substantially less than the length of the slot and such as to slidably engage the sides of the slot, said clip being swingable about the free extremity of said bearing portion relatively to said bolt for adjusting the position of said extremity of the arcuate portion to accommodate cover plates of different thicknesses.

5. For use in a bridge tie anchor, an elongated resilient clip rectangular in cross section and having a tie engaging flat end bearing portion provided with projections to bite into a tie, 15 said clip also having its opposite end portion arcuately curved and disposed at one side of the plane of said flat end bearing portion and having a free extremity to underly and engage a part of a bridge, there being an elongated slot extending longitudinally of said clip and through said arcuately curved portion between said flat end bearing portion and the free extremity of said arcuately curved portion, the imaginary center of said arcuately curved portion being located at the other side of the plane of said tie-engaging flat end bearing portion, said slot having a length substantially greater than the diameter of 20 a bolt to be inserted therethrough and having a width such that the bolt will slidably engage the sides of the slot.

6. For use in a bridge tie anchor, an elongated resilient clip rectangular in cross section and having a tie engaging flat end bearing portion provided with projections to bite into a tie, 30 said clip also having its opposite end portion arcuately curved and spaced by an intermediate portion from said flat end bearing portion and having a free bridge engaging extremity, there being an elongated slot extending longitudinally of said clip and through said arcuately curved portion between said intermediate portion, and the free extremity of said arcuately curved portion to receive a bolt disposed in radial relation to said arcuately curved portion, said intermediate portion being angularly related to and at one side of the plane of said flat end bearing portion and the imaginary center of said arcuately curved portion being located at the other side of the plane of 35 said flat end portion the length of said slot being substantially greater than the diameter of a bolt inserted through the slot and the width of the slot being such that the sides of the slot will slidably engage said bolt.
